(57) **CLAIM**

The ornamental design for a pacifier, as shown and described.

DESCRIPTION

FIG. 1 is a front elevation view of a pacifier showing our new design;

FIG. 2 is a rear elevation view thereof;

FIG. 3 is a top plan view thereof, the bottom plan view being a mirror image thereof;

FIG. 4 is a right side elevation view thereof;

FIG. 5 is a left side elevation view thereof;

FIG. 6 is a cross-sectional plan view of the pacifier of FIG. 1, taken in the direction of line 6-6 of FIG. 1;

FIG. 7 is a cross-sectional elevation view of the pacifier of FIG. 1, taken in the direction of line 7-7 of FIG. 1;

FIG. 8 is a top, front, right perspective view of the pacifier of FIG. 1; and,

FIG. 9 is a bottom, rear, left perspective view thereof.

1 Claim, 9 Drawing Sheets
